Primary Examiner — Cathron C Brooks*Assistant Examiner* — W. A. Teddy Falloway(74) *Attorney, Agent, or Firm* — Ralph E. Jocke; Walker & Jocke(57) **CLAIM**

An ornamental design for a can carrier, as shown and described.

DESCRIPTION

FIG. 1 is a front top left perspective view showing my new design for a can carrier.

FIG. 2 is a back top left perspective view thereof.

FIG. 3 is a front bottom left perspective view thereof.

FIG. 4 is a front view thereof.

FIG. 5 is a back view thereof.

FIG. 6 is a left side view thereof.

FIG. 7 is a right side view thereof.

FIG. 8 is a top view thereof.

FIG. 9 is a bottom view thereof.

FIG. 10 is a front top left perspective view thereof with a can divider shown in phantom.

FIG. 11 is a back top left perspective view thereof with a can divider shown in phantom; and,

FIG. 12 is a front top left perspective view with a can divider and cans shown in phantom.

The broken lines showing a divider and cans in FIGS. 10-12 illustrate environment. All other broken lines illustrate portions of the can carrier. The broken lines form no part of the claimed design.
